TOILET ARTICLE AND METHOD OF MANUFACTURING THE SAME

Application filed February 19, 1931. Serial No. 517,078.

An object of the invention is to provide a toilet article having a pumice back with a cavity in which the back of a brush is secured.

Another object of the invention is to provide a toilet article having a back formed of powdered pumice bound with silicate of soda.

Still another object of the invention is to provide a method of manufacturing the toilet article in which powdered pumice is mixed with silicate of soda as a binder and is pressed in a mould and annealed, a portion of the mould forming a cavity in the finished article and in this cavity the back of a brush is secured. The said portion of the mould forming the cavity is larger than the back of the brush, as the moulded pumice will shrink when annealed and it is desirous that the back of the brush fit the mould tightly at the cavity.

Additional objects of the invention will appear in the following specification in which the preferred form of the invention is described.

In the drawing similar reference characters refer to similar parts in the several views, of which

Figure 1 is a perspective view illustrating the toilet article,

Figure 2 is an enlarged inverted plan view of the toilet article, and

Figure 3 is a sectional view on the line 3—3 of Figure 1.

In the manufacture of the toilet article, a mould is prepared having a projection to form the cavity 5 in the pumice and powdered pumice, mixed with silicate of soda, is disposed in this mould and is annealed, the mould being removed from the powdered pumice early in the annealing process so that the shrinkage of the powdered pumice with the silicate binder will not serve to break or crack the powdered pumice with its silicate binder.

It is important that the portion of the

mould forming the cavity 5 be greater in length and width than the back 6 of a brush 7, so that with the shrinkage the pumice back at its cavity 5 will be of a size which will permit the back 6 of the brush 7 to fit the cavity 5 tightly to give a neat appearance. Preferably the pumice has another opening 8 at its top and the portion of the mould forming the cavity 5 has rounded ends 9 to fit the rounded ends of the back 6 of the brush. 50

The back 6 of the brush is manufactured of non-expansive material, such as bakelite, so that when the back 6 of the brush 7 is secured by glue, or other means, in the cavity 5 in the pumice back 4, moisture will not serve to warp or break the back 6 of the brush and the back 6 of the brush will remain secured in the cavity 5 of the pumice back 4 at all times ready for service. 60

The toilet article, when the manufacture is completed, will have a pumice back 4 with a cavity 5 in which the bakelite back 6 of the brush 7 is secured by glue, or other means. The brush 7 has bristles 10 which may be of any desired length and any desired stiffness. 65

What is claimed is:—

1. In a toilet article, a back of powdered pumice bound with silicate of soda and having a cavity therein, and a non-expansive brush back secured to the pumice back in the cavity. 75

2. In a toilet article, a pumice back having a cavity, and a non-expansive brush back secured to the pumice back in the cavity.

3. In a toilet article, a block of moulded powdered pumice bound with silicate of soda, a cavity in one face of the block, and a brush having a substantially non-expansive and non-contractible back, secured to said block within the said cavity thereof by an adhesive 80 and about which back the moulded pumice block is contracted. 85

4. In a toilet article, a contracted block of moulded powdered pumice bound with silicate of soda and having an integrally formed 90

peripheral wall of the same material up-standing therefrom, and a brush having a substantially non-expansible and non-contractible back positioned against the block with the interior of said wall contiguous to the edge of said back and about which said wall is contracted, said wall being of substantially the same height as the thickness of the back of the brush whereby the outer face of the brush back is flush with the upper edge of said wall, and additional means co-operating with the wall of the moulded pumice block to secure the back of said brush fixedly to said block.
